UNITED STATES PATENT OFFICE.

RICHARD F. BARRY, OF NEWTON, MASSACHUSETTS, ASSIGNOR TO FANNIE G. BARRY, OF SAME PLACE.

EYELETING-MACHINE.

SPECIFICATION forming part of Letters Patent No. 562,368, dated June 23, 1896.

Application filed September 9, 1895. Serial No. 561,877. (No model.)

To all whom it may concern:

Be it known that I, RICHARD FREDERICK BARRY, of Newton, in the county of Middlesex and State of Massachusetts, have invented 5 certain new and useful Improvements in Eyeletting-Machines, of which the following is a specification.

This invention relates to eyeletting-machines, such as that shown in a former patent 10 granted to me August 29, 1893, No. 504,295. In the machine shown in that patent a number of interchangeable supports or anvils are shown, each constructed to support an eyelet or an equivalent device, such as a lacing-hook, 15 and each adapted to coact with a setting-die, and a plunger is employed which has provisions for interchanging of dies.

My improvement involves a single bed-plate with a plurality of supports or anvils simultaneously adjustable, so that it is not necessary to disconnect one anvil from the machine in substituting another for it. In this the invention may be said to chiefly reside, although there are other features which are 25 claimed.

The accompanying drawings illustrate an embodiment of the invention.

Figure 1 shows the machine partly in side elevation and partly in section. Fig. 2 shows 30 a section on line 2 2, Fig. 1, and a plan of the parts below said line. Fig. 3 shows a sectional view of the bed-piece. Figs. 4, 5, and 6 show end views and longitudinal sections of the male dies employed. Figs. 7, 8, and 9 are 35 sectional views of the bed-piece and side views of the coöperating dies.

The letter *a* designates the main casting or supporting frame, which is of the form commonly employed in hand-stamps. The horizontal base portion of said frame is bored vertically to receive the stem *b* of a circular bed-piece *b'* which extends over the base. Said bed-piece is bored to receive two annular eyelet supports or anvils *d d*, adapted to support 40 the annular outer ends or flanges of eyelets, said dies being of different sizes, and having central orifices to receive the finger of the coöperating eyelet-setting die *f*. (Shown in Figs. 4 and 7.) A circular plate *b²* is fastened on 45 the bed-piece, and is provided with notches *b⁴ b⁵*. The bed-piece is provided below said

notches with recesses *b⁷ b⁷*, as indicated in Figs. 1, 8, and 9 and by dotted lines in Fig. 2, said recesses *b⁷* being wider and deeper than the notches *b⁴ b⁵* and formed to receive the 55 heads of lacing-studs and eyelet-hooks, as shown in Figs. 8 and 9. The shanks of the said studs and hooks project upwardly from the plate *b²* and are held in position to co-operate with setting-dies. The bed-piece is 60 thus adapted to hold different articles, such as eyelets and lacing hooks or studs of different sizes, the notched portions of the plate *b²* constituting hook or stud supporting anvils.

The supporting-frame is provided with a 65 seat *a'*, which supports the bed-piece *b'*, the stem *b* of said bed-piece passing through a socket *a²* extending through the seat *a'* and to the bottom of the frame, as shown in Fig. 1. Below the frame is a disk *b⁸*, affixed to the 70 stem *b*, said disk having in its upper surface a series of recesses *b⁹* corresponding in number and position to the eyelet and lacing-stud holding devices above described. A spring-pressed latch or pin *i*, movable vertically in a 75 socket in the base *a*, is adapted to yieldingly engage either of the recesses *b⁹* and thus hold the bed-piece in either of a series of positions. The seat *a'* and the socket in which the stem *b* is journaled coöperate in firmly supporting 80 the bed-piece *b'* and preventing its displacement either downwardly or laterally.

The letter *j* designates the plunger, which is arranged to slide vertically in the overhanging portion of the frame and is held up 85 by a spring *j'*. A cam-lever *k*, pivoted to the frame, bears on the top of the plunger, and is used to depress the same. The plunger is made tubular for a portion of its length from its lower end, for the reception of the shank 90 of any one of the dies *f' f²*, and the shank of each die is formed with an encircling groove *m⁸* for engagement of a pin *n* on a flat spring *n'*, fastened to the plunger. By these means each die is held in the plunger in such a manner as to permit its ready removal. 95

The die *f* is for setting eyelets *m* and coöperates with either of the eyelet-supporting anvils *d*, the tube of the eyelet projecting upwardly from the anvil *d* to receive the projecting finger of the die *f*, as shown in Fig. 7. 100

The die *f'* is for setting lacing-hooks *m'*,

which are provided with eyelets or eyelet-shaped shanks. This die acts in conjunction with a hole b^6 in the plate b^2 at the inner end of the notch b^5 , the eyelet portion of the hook 5 being brought in line with said hole by fitting the throat of the hook over the edge of the plate, as shown in Fig. 8, the recess b^7 of the plate permitting the hook to be moved over far enough to bring its tubular portion in line 10 with the hole.

The die f^2 is for setting lacing-studs m^2 , and is formed with a pyramidal spur f^3 , having the sides 1 2 3 4, as shown in Fig. 6. This die works in conjunction with the part of the 15 plate b^2 having the notch b^4 , said notch permitting the stud to stand in proper alinement with the plunger. The object of the pyramidal formation above mentioned is to cause the tubular part of the stud to be cut at four 20 equidistant points by the angles of the die, formed by the sides 1 2 3 4, so that it will be divided into four prongs.

It will be seen that the machine can be 25 readily adapted for either setting fast-color and other eyelets, lacing-hooks, or lacing-studs, by manipulation of the bed-piece and insertion of the proper die in the plunger.

The machine organized as described will 30 set various sizes of eyelets, eyelet-hooks, and lacing-studs, and is well adapted for setting so-called "fast-color" eyelets, and fast-color and agatine lacing studs and hooks.

I claim—

1. A machine for setting eyelets and other 35 analogous fastening devices, the same comprising a supporting-frame having a base and an overhanging part; a vertically-movable plunger in said overhanging part having means for interchangeably holding different 40 setting-dies; a bed-piece recessed from its circumference toward its center at one or

more points and bored through at others, said bed-piece being mounted to rotate on a vertical axis in the base and having such axis of rotation out of alinement with the 45 longitudinal center of said plunger; one or more tubular anvils set in the holes bored in the bed-piece and formed at their upper ends to support eyelets; a plate fastened on the bed-piece and notched over the recesses 50 therein and formed to accommodate the said tubular anvil or anvils; and means for locking the bed-piece in different positions, all arranged substantially as and for the purpose described.

2. A machine for setting eyelets and other analogous fastening devices, the same comprising a supporting-frame having a seat, a socket extending downwardly therefrom, and a part overhanging said base; a vertically- 60 movable plunger in said overhanging part having means for interchangeably holding different setting-dies; a bed-piece bearing on said seat and having a stem journaled in said socket, said bed-piece also having a plurality 65 of anvils each adapted to coöperate with a die held by said plunger; a plate affixed to said stem below the base and provided with a number of depressions in its upper side; and a latch or bolt in the base, spring-pressed 70 downwardly against the said plate and adapted to enter the depressions therein to hold the bed-piece at different position, and to keep the latter pressed down upon its seat.

In testimony whereof I have signed my 75 name to this specification, in the presence of two subscribing witnesses, this 3d day of September, A. D. 1895.

RICHARD F. BARRY.
